Claims priority, application Great Britain Dec. 6, 1954

6 Claims. (Cl. 230—132)

This invention relates to axial-flow fluid machines comprising a rotor of the type which includes a rotor drum or disc structure with blades pivoted at its periphery, hereinafter called "a rotor of the type referred to." Axial-flow compressors of aircraft gas-turbine engines often include such rotor structures.

The rotor drum or disc structure may comprise a number of axially-spaced discs, each having a row of blades at its periphery; in such a rotor drum structure the discs having pivoted blades are usually provided with radially-extending peripheral flanges to receive the blade-mounting pivot pins and the blades have lugs at their root ends overlapping the flanges and also receiving the pivot pins.

It is often desirable to supply a fluid to the blades of an axial-flow fluid machine; for instance, in the case of the first-stage blading of an axial-flow compressor of an aircraft gas-turbine engine it is often desirable to supply a heating fluid to the blading for the purpose of preventing or reducing ice formation on the blading.

This invention has for an object to provide a rotor structure for an axial-flow fluid machine having pivoted blading and improved means whereby a fluid may be supplied to the pivoted blading.

According to the present invention, in a rotor of the type referred to the inlet ends of fluid passages in the pivoted blades and fluid supply passages in the rotor structure meet at positions offset from the respective pivot pins in surfaces of the blade roots and the rotor structure which are urged into contact by loads experienced in operation.

According to a feature of the present invention, where the blades are pivoted blades of the rotor of an axial-flow compressor, the inlet end of a fluid passage in each of a plurality of the pivoted blades is arranged to open to an upstream-facing surface of the blade root, the surface being at right angles to the pivotal axis of the blade and the passage opening at a position in the root offset from the bore for the pivot pin of the blade, an adjacent peripheral flange on the rotor structure is provided with apertures in its downstream-facing surface to overlap each of said inlets in the blade roots, said downstream surface also being at right angles to the pivotal axis, the upstream-facing surface of the blade root being held against the downstream-facing surface of the flange by the gas load on the blade, and there is provided an annular manifold as part of the rotor structure to supply fluid to the apertures in the peripheral flange and thus to the inlets in the blade roots.

According to one preferred arrangement, an annular disc is secured to the rotor structure, and the annular disc and the peripheral flange by having parts thereof in axial abutment form a manifold space between them. In such a construction it is preferred to arrange that the fluid cannot flow from the manifold through the apertures in the flange for the pivot pins; for instance the annular disc may be provided with recessed lands which abut the peripheral flange around the apertures for the pivot pins, so sealing them from the fluid space of the manifold.

In another preferred arrangement, a pair of annular discs are secured together to form a manifold space between them, the fluid being fed to the space for distribution, the discs are mounted on the rotor structure in spaced relation to the peripheral flange which has the apertures overlapping the inlets in the blade roots and transfer pieces are provided which fit in the apertures and in aligned apertures in one of the discs to convey the fluid from the manifold space to the peripheral flange and thus to the inlets in the blade roots.

Two embodiments of the invention as applied to an anti-icing apparatus for pivoted blades of an axial-flow compressor of an aircraft gas-turbine engine will now be described. The description makes reference to the accompanying drawings in which:

Figure 1 is an axial section through part of the compressor,

Figure 2 is a similar view at an angularly spaced location,

Figure 3 is a section on the line III—III of Figure 2,
Figure 4 is a view in the direction of arrow IV on Figure 1, parts being broken away, and the section lines of Figures 1 and 2 being indicated at I—I and II—II respectively,

Figures 5 and 6 correspond to Figures 1 and 2 and show a second embodiment,

Figure 7 is an enlargement of part of Figure 6, and Figure 8 corresponds to Figure 4 and shows the section lines for Figures 5 and 6 at V—V and VI—VI respectively.

Referring to Figures 1 to 4 showing the first embodiment, the rotor of the axial-flow compressor comprises a central hollow shaft 10 on which there are mounted in axially-spaced relation a number of blade-carrying discs

35 (not shown) for the rotor blades of the second and subsequent stages of the compressor, and the peripheries of the discs are held in spaced relation by spacer rings 11. The upstream end of the shaft 10 has secured to it an axial extension 13, and these parts abut over radial flanges

40 14, 15 and the radial flanges support the disc 18 carrying the first-stage rotor blades. For this purpose the flange 15 on the shaft extension 13 is axially thickened and is provided with a frusto-conical outward flange 16 which is inclined away from the flange 14 at the upstream end

45 of the shaft 10 and terminates at its outer end in a radial portion 17. The disc 18 carrying the first-stage rotor blades 19 has an axially-thickened portion 20 to abut the flange 15 on the shaft extension 13, a frusto-conical portion 21 extending outwards to an outer radial portion 22

50 which abuts the outer radial portion 17 of the flange 16 and is secured to it. Bolts 23 extend through the thickened portion 20 of the disc and the flange 15 of the shaft extension 13 and through the radial flange 14 on the shaft 10. There is thus formed a triangular-section annular space 24 which is used as a primary manifold for a hot air supply which is to be conveyed to drillings 25 in the first-stage blading 19.

The first stage blading 19 is pivoted to the rim 26 of the disc 18 the rim having a number of radial flanges 27 and the rotor blading 19 having corresponding lugs 28 on its root portion, the lugs 28 being intercalated with the flanges 27, and the lugs and flanges having pivot pins 29 extending substantially axially through them. The flanges 27 and lugs 28 have their contacting surfaces at right angles to the axes of the pivot pins 29.

The hot air is conveyed to the primary manifold 24 from any convenient source, such as the delivery of the compressor, through stationary structure whence it passes

70 in a generally radial direction through slots 20a in the thickened portion 20 of disc 18.

The hot air is conveyed from the primary manifold

24 to a distributing manifold which is formed by attaching an annular disc 30 to the blade-carrying disc 18.

The manifold-forming disc 30 has at its inner radius a radial portion 31 which abuts the radial portion 22 on the blade-carrying disc 18, and the bolts 32 which hold the manifold-forming disc 30 in position are those which extend through the outer radial portions 22, 17 of the blade-carrying disc 18, and the shaft extension 13. The manifold-forming disc 30 has an axial portion 33 extending from the outer radius of the radial portion 31 and at the end of the axial portion a further radial portion 34 which extends outwardly into contact with a short axial flange 35 provided at the outer periphery of the upstream radial flange 27. The axial portion 33 is sufficiently flexible for the centrifugal loads experienced in operation to cause a good seal to be maintained between the manifold-forming disc 30 and the short axial flange 35.

The inner radial portion 31 of the manifold disc 30 has a number of radial channels 36 cut in it between its bolt holes, the channels stopping short of its inner periphery, and drillings 37 are formed in the blade-carrying disc 18 to connect the channels 36 with the interior of the triangular-section primary manifold 24.

The fluid flows from the primary manifold 24 through the drillings 37 and the channels 36 into a space 38 between the inner surface of the blade-carrying disc rim 26, and the axial portion 33 and inner part of the second radial portion 34 of the manifold-forming disc 30. The second radial portion 34 of the manifold-forming disc 30 has a number of lands 39 extending axially from it, the number and spacing of the lands being equal to the number and spacing of the pivot pins 29. Each land 39 extends into abutment with the upstream face of the upstream radial flange 27 on the disc rim 26, and has a central cavity 40 (Figure 2) into which the end of the associated pivot pin 29 projects. Thus the pivot-pin-receiving holes in the upstream radial flange 27 are sealed off from the fluid manifold 38. The upstream radial flange 27 is formed with a number of holes 41 (Figures 1 and 4) which extend to its downstream surface to afford the outlets from the manifold. These holes are offset from the pivot pin holes in the flange 27.

Each of the first-stage rotor blades has its drilling 25 running lengthwise thereof adjacent its leading edge and the drilling extends into the root portion to terminate radially outside the pivot pin holes in the lugs 28 and there is a short axially-extending drilling 42 to the lower end of the main drilling 25 from a point in the upstream face of the upstream lug 28 so dimensioned and arranged as to overlap the corresponding outlet hole 41 in the radial flange 27 to permit fluid to be transferred into the passages in the blades 19, regardless of the angular position of the blades about their pivot axes at any given instant in operation.

The upstream face of the upstream lug 28 of the blade and the downstream face of the upstream radial flange 27 are, as stated above, made square with the axis of the associated pivot pin 29. Now, although there will be a small axial clearance between the radial flanges 27 on the disc rim 26 and the lugs 28 on the rotor blades 19 through which the fluid might leak, the resultant force acting axially on the blades 19 due to the pressure rise across them will urge the squared surfaces into contact to give a true face joint which does not prevent pivoting of the blades 19 whilst substantially avoiding fluid leakage. It will also be clear that the blades 19 are located in the radial sense with respect to the disc by the pivot pins 29, since the centrifugal effect acting on the blades takes up any clearance between the blade and the pin, or the pin and the disc.

To ensure that fluid at high pressure does not escape into any space that may momentarily occur between the downstream face of the upstream radial flange 27 and the upstream face of the upstream lug 28 due to a slight

disturbance, thereby tending to blow the lug and flange apart, a small groove 44 (Figures 1 and 4) is formed in the upstream face of the lug around the opening of the drilling 42, and the groove is placed in communication with the space radially outside the disc rim. In this way any leakage fluid may escape freely, and it is arranged that the area of the face around the drilling, within the groove, is such that the load which may be applied to it by the pressure of the fluid is much less than the forward axial load on the blade.

In operation, when it is desired to prevent or reduce ice formation on the first-stage rotor blading 19, hot air is supplied to the triangular-section primary manifold 24, for example from the delivery of a later stage of the compressor, and it then flows therefrom in the manner described above into the space between the upstream radial flange 27 and the manifold disc 30. The hot air then flows through the holes 41 in the upstream radial flange 27 into the inlet drillings 42 in the blade roots and thus to the leading edge drillings 25.

In the second embodiment (Figures 5 to 8), the compressor rotor comprises a central hollow shaft 50, and in this case all the rotor discs 51, including that carrying the first-stage rotor blading, are splined on the shaft 50 with spacer rings 53 between their rims 54. The splined connection for the first-stage disc 51 is shown at 52.

In this construction, the first-stage blade-carrying disc 51 has a number of radial flanges 55 on its rim 54 with sets of aligned holes in them to receive pivot pins 56 by which the rotor blading is connected to the disc. Each rotor blade 57 has lugs 58 at its inner end which are intercalated with the radial flanges 55 on the disc rim 54 and are bored to receive the associated pivot pin 56, and moreover, the blade is provided with a longitudinal passageway 59 extending adjacent the leading edge from its tip to within the root end of the blade where it is met by a drilling 60 (Figure 7) from the upstream face of the upstream lug 58 to provide an inlet to the passage 59. As in the previous construction, the upstream face of the lug 58 on the blade and the downstream face of the upstream radial flange 55 are arranged to be square with the axis of the pivot pin 56, thus to make a true face joint.

Hot air is fed to the inlet drilling 60 in the following way.

The front end of the rotor shaft 50 is mounted in a bearing accommodated within a bearing housing 61 which is formed with a pair of radially-spaced annular flanges 62 which extend axially from the bearing housing towards the first-stage blade-carrying disc 51. A hot air supply passage 63 in the bearing housing leads to the space between the two flanges.

Co-operating with the two flanges 62 are a pair of labyrinth seal members 64, 65 of which member 64 is formed on the blade-carrying disc adjacent its centre and co-operates with the inner surface of the innermost of the two flanges 62, and member 65 is formed at the inner periphery of a manifold-forming disc 66 and co-operates with the inner surface of the outermost flange 62.

The manifold-forming disc 66 is secured by radially-spaced sets of bolts 67 to the blade-carrying disc 51 on the upstream side thereof, and the blade-carrying disc 51 and the manifold-forming disc 66 are formed with abutting bosses 68, 69 where the bolts pass through them so that the greater part of these discs are spaced apart and the space 70 between the discs communicates with the space between the two flanges 62 on the bearing housing to receive hot air therefrom.

Towards its outer edge the manifold-forming disc 66 is cranked in section to follow the contour of the blade-carrying disc rim 54 and to have an axially-extending portion 71, which is spaced radially inwards of the inner surface of the blade-carrying disc rim 54, and a radial

portion 72 which extends outwardly alongside the upstream radial flange 55 on the rim 54.

The manifold-forming disc 66 forms the upstream wall of the hot air distribution manifold and the radial portion 72 has at its outer edge a thickened bead 73 which projects towards the upstream radial flange 55.

A ring 74 having substantially the same radial extent as the radial portion 72 of the disc 66 is secured to the radial portion 72 to be between it and the radial flange 55. The ring 74 has an outer peripheral portion in contact with and welded to the bead 73 and an inner peripheral portion 75 extending axially towards and into contact with the radially inner edge of the blade-carrying disc rim 54.

The ring 74 is of corrugated form with the corrugations extending radially and thus both surfaces of the ring 74 have a series of circumferentially-alternating lands and grooves which extend from its inner edge to close to its outer edge. The lands 76 projecting from the upstream face of the ring abut and are welded to the downstream surface of the radial portion 72 of the manifold-forming disc 66, and the intermediate parts, which afford the grooves on the upstream face of the ring 74, have adjacent their outer ends holes 77 (Figures 5, 6 and 7) which run through the ring to the downstream surface thereof, and so open to the centres of the lands on the downstream surface of the ring.

A number of axially-bored generally cylindrical transfer pieces 78 are provided which fit in the holes 77 in the ring 74 and in aligned holes 79 in the radial flange 55, the transfer pieces 78 having circumferential flanges 80 adjacent their mid-length which limit the axial travel of the pieces 78 by abutting the upstream face of the radial flange 55 or the downstream face of the ring 74.

The hot air flows outwards from space 70 into the spaces between the lands 76 and then flows through holes 77, transfer pieces 78 and holes 79 into the inlet drillings 60.

I claim:

1. A rotor for an axial-flow fluid machine comprising rotor structure, a ring of blades at the periphery of the rotor structure, each of said blades having a root, pivot pins engaging said roots and said rotor structure pivotally to connect the blades to the rotor structure so as to allow a limited pivotal movement of the blades relative to the rotor structure, said roots having surfaces which are urged into contact with corresponding surfaces of the rotor structure by loads experienced in operation, said blades having internal fluid passages with inlets thereto opening in said surfaces of the roots at positions offset from the respective pivot pins, and fluid supply means in the rotor structure leading to outlets in said corresponding surfaces of the rotor structure, said outlets overlapping the inlets in the roots, whereby the fluid is transferred from said outlets to said inlets in the blade roots across surfaces maintained in contact by loads acting on the blades in operation of the machine.

2. A rotor for an axial-flow compressor comprising rotor structure having a peripheral flange with a flat downstream-facing surface, there being pivot-pin-receiving holes in the peripheral flange, a ring of blades at the periphery of the rotor structure, each of said blades having a root with a pivot-pin-receiving hole therein, pivot pins extending through the holes in said roots and said peripheral flange of the rotor structure pivotally to connect the blades to the rotor structure and to allow a degree of free pivotal movement of the blades relative to the rotor structure, said roots having flat upstream-facing surfaces, both said downstream-facing surface of the peripheral flange and said upstream-facing surfaces of the roots being at right angles to the pivotal axes of the blades, and said surfaces being urged into contact by loads experienced in operation, fluid passages in the blades having inlets thereto opening through said upstream-facing surfaces of the roots at positions offset

from the pivot-pin-receiving holes therein, apertures in said downstream-facing surface to overlap each of said inlets in the roots, whereby the fluid is transferred from said apertures to said inlets in the blade roots across surfaces maintained in contact by loads acting on the blades in operation of the machine, and said rotor structure comprising annular fluid supply manifold means connected to supply fluid to the apertures in the peripheral flange and thus to the inlets in the blade roots.

3. A rotor as claimed in claim 2, wherein said manifold means comprises a pair of annular discs secured together to define a manifold space between them, the fluid being fed to the space for distribution, the discs being mounted on the rotor structure in spaced relation to said peripheral flange, and transfer pieces having bores therein which fit in the apertures in the peripheral flange and in aligned apertures in one of the annular discs, the bores serving to convey the fluid from the manifold space to the apertures in the peripheral flange and thus to the inlets in the blade roots.

4. A rotor as claimed in claim 3, wherein the annular discs are sealed together at their outer peripheries, and one of the annular discs is of radially corrugated form to provide alternate lands and grooves, the lands being in contact with the other annular disc and the corresponding grooves forming distributing spaces leading to the apertures in the disc receiving the transfer pieces.

5. A rotor for an axial flow compressor comprising rotor structure having a peripheral flange with a flat downstream-facing surface, there being pivot-pin-receiving holes in the peripheral flange, a ring of blades at the periphery of the rotor structure, each of said blades having a root with a pivot-pin-receiving hole therein, pivot pins extending through the holes in said roots and said peripheral flange of the rotor structure pivotally to connect the blades to the rotor structure and to allow a degree of free pivotal movement of the blades relative to the rotor structure, said roots having flat upstream-facing surfaces, both said downstream-facing surface of the peripheral flange and said upstream-facing surfaces of the roots being at right angles to the pivotal axes of the blades, and said surfaces being urged into contact by loads experienced in operation, fluid passages in the blades having inlets thereto opening through said upstream-facing surfaces of the roots at positions offset from the pivot-pin-receiving holes therein, apertures in said peripheral flange opening to said downstream-facing surface thereof, said apertures overlapping each of said inlets in the roots, and an annular disc secured to the rotor structure and co-operating with said peripheral flange to define a fluid manifold space, said apertures communicating with the manifold space, whereby fluid is transferred from the manifold space through the apertures to the inlets in the blade roots across said surfaces which are urged into contact by loads experienced in operation, the annular disc having recessed lands projecting from it into abutment with the peripheral flange around the holes therein for the pivot pins so sealing the holes from the manifold space.

6. A rotor for an axial-flow compressor comprising rotor structure having a peripheral flange with a flat downstream-facing surface, there being pivot-pin-receiving holes in the peripheral flange, a ring of blades at the periphery of the rotor structure, each of said blades having a root with a pivot-pin-receiving hole therein, pivot pins extending through the holes in said roots and said peripheral flange of the rotor structure pivotally to connect the blades to the rotor structure and to allow a degree of free pivotal movement of the blades relative to the rotor structure, said roots having flat upstream-facing surfaces, both said downstream-facing surface of the peripheral flange and said upstream-facing surfaces of the roots being at right angles to the pivotal axes of the blades, and said surfaces being urged into contact by loads experienced in operation, fluid passages in the

blades having inlets thereto opening through said upstream-facing surfaces of the roots at positions offset from the pivot-pin-receiving holes therein, apertures in said downstream-facing surface to overlap each of said inlets in the roots, whereby the fluid is transferred from said apertures to said inlets in the blade roots across surfaces maintained in contact by loads acting on the blades in operation of the machine, and said rotor structure comprising annular fluid supply manifold means connected to supply fluid to the apertures in the peripheral flange and thus to the inlets in the blade roots, and the upstream-facing surfaces of the blade roots having each a groove formed therein around the inlet of the respective

5

passage, the grooves being in communication with the space radially outside the peripheral flange of the rotor.
